United States Patent Office.

DONALD D. MACKAY, OF WHITESTONE, NEW YORK,

Letters Patent No. 69,456, dated October 1, 1867.

IMPROVEMENT IN SASH-LOCKS AND STOPS.

The Schedule referred to in these Letters Patent and making part of the same.

TO ALL WHOM IT MAY CONCERN:

Be it known that I, DONALD D. MACKAY, of Whitestone, in the county of Queens, and State of New York, have invented certain new and useful Improvements in Sash-stops and Locks, and I do hereby declare that the following is a full, clear, and exact description of the same, reference being had to the accompanying drawings, making a portion of this specification, in which—

Figure 1 is a front view and partial section of a window furnished with a sash-stop and lock constructed according to my invention.

Figure 2 is a detached edge view of a sash furnished with the same.

Similar letters of reference indicate corresponding parts in both figures.

This invention consists in a pivoted spring-catch, a sliding operating-rod, and a laterally or outwardly projecting knob, situated in the edge of a window-sash, and arranged in relation with each other, and with a notch or recess formed in the side of the window-frame, in such manner that a very effective device for locking down the sash is secured. The invention further consists in the arrangement, with reference to the aforesaid parts of sliding friction-bars, furnished with rollers at their outer extremities, and acted upon by spiral springs, whereby the invention may not only be employed for locking down the sash when required, but also serves the purpose of retaining the same at any desired height when raised.

To enable others to understand the construction and operation of my invention, I will proceed to describe it with reference to the drawings.

A represents the window-sash, and B the frame thereof. Secured by screws or other suitable means to one of the lateral edges of the sash A is a longitudinal metallic plate, a, which has formed upon each of its ends a small box or case, a*, which receives a sliding-bar or piece, b, as shown in fig. 1. The said sliding-bars are furnished at their outer ends with small rollers, a', working on horizontal axes, and are each formed or furnished with inwardly-extending stems b', which pass through holes or slots in the bottom or inner ends of the cases a*. A spiral spring, c, placed upon the stems b', between the main portions of the aforesaid bars or pieces b and the inner ends of the cases a, forces the said bars outward, so that the rollers a' are pressed against the contiguous inner side of the window-frame B, with such force as to retain the sash at any desired elevation, as hereinafter further set forth. Formed in the plate a, at or near the centre of the same, is a vertical-slot, d', which communicates with a deep recess, b*, provided in the edge of the sash B. Working through this slot is a catch, e, which is pivoted at its lower end, as shown at e', and is pressed outward by a spring, e*, situated within the recess b*. A sliding-rod, f, has its outermost end pivoted to the upper extremity of the catch e, and its opposite or inner end is furnished with a knob, c*, which projects laterally therefrom through a suitable slot formed in the front side of the sash, as indicated in blue outline in fig. 1.

When the sash is down in the position shown in fig. 1, the catch e is forced by the spring e* outward, so that it fits into a notch, f, formed in the adjacent side of the frame A, and consequently prevents the sash from being raised from the outside of the window. When it is desired to raise the sash, the catch e is brought inward from the recess f* by sliding the rod f by means of the knob c*, and the sash being then elevated, the spiral springs c' press the slides or bars b outward, with their rollers a', against the adjacent side of the frame B with sufficient force to insure the retention of the sash A at the required height, by the friction of that edge thereof opposite the one at which the aforesaid slides or bars b are placed upon the corresponding side of the window-frame.

What I claim as my invention, and desire to secure by Letters Patent, is—

1. The spring-catch e, pivoted at its lower end, sliding-rod f, and knob c*, arranged in relation with the spring-rollers a', and the sash A, for operation substantially as set forth, the whole forming a combined sash-stop and lock, as described.
2. The sliding-bars b, furnished with rollers a', and operated by spiral springs c', as arranged and operating in relation with the sash A; substantially as and for the purpose specified.

D. D. MACKAY.
